UNITED STATES PATENT OFFICE

BURT A. PETERSON, OF ROCKFORD, ILLINOIS, ASSIGNOR TO BARBER-COLMAN COMPANY,
OF ROCKFORD, ILLINOIS, A CORPORATION OF ILLINOIS

WARPING APPARATUS

Application filed September 11, 1929. Serial No. 391,796.

This invention has particular reference to means for guiding the running yarn, to means for detecting breakage or excessive slackening of the yarn, and to means for controlling the detectors.

When drawing yarn off the ends of yarn masses which are non-rotatably mounted, it is necessary to provide means to prevent the yarn from kinking when the warper or other rewinding mechanism stops, as the yarn unwinds so freely from such yarn masses that kinks formed at the time of stopping will not be straightened out when the warper is again set in operation. In a certain prior warper to which yarn is supplied from cross-wound conical yarn masses non-rotatably mounted, there is a tension device adjacent to each conical yarn mass which acts upon the thread at all times. This tension device is effective to insure that kinks shall be straightened out upon a restarting of the warper, but inasmuch as the tension device acts at all times it limits the speed at which the warper may be operated. One of the important objects of the present invention is to provide a tension device which shall act only when needed, namely when starting the warper, and which consequently places no tension upon the yarn in normal operation of the machine, and therefore by lessening yarn breakage makes possible the attainment of a much higher warping speed.

In the prior art warper just referred to it is impracticable to make the tension devices uniform in their action, hence they place a varying amount of tension upon the yarn being warped. Since the tension devices of the warper herein disclosed do not act during normal operation of the warper, there is uniformity of tension of the yarn being warped.

In the accompanying drawings:

Figure 1 is a fragmental side view of a warper creel embodying the features of my invention.

Figs. 2 and 3 are fragmental perspective views of one of the yarn guiding and detecting units of the creel.

Fig. 4 is a front elevation of said parts.

Fig. 5 is a section on line 5—5 of Fig. 4.

Fig. 5^a illustrates the normal or intermediate position of the control bar.

Fig. 6 is a plan view showing the rear portion of the warper and the forward portion of the creel.

Fig. 7 is a schematic view of the starting and stopping mechanism and the electric circuits.

Fig. 8 is a view taken in the plane of line 8—8 of Fig. 6, showing the mechanism in running position.

Fig. 9 is a view taken in the plane of line 9—9 of Fig. 8.

Fig. 10 is a view similar to Fig. 8, but showing in full lines the apparatus in the threading position, and in dotted lines the position assumed in the stop position.

While the invention is susceptible of use in connection with various kinds of machinery for rewinding yarn, I have herein shown the invention in connection with a warper and its creel. Reference may be made to my Patent No. 1,672,470 dated June 5, 1928, for a disclosure of a warper which may be used in connection with the present invention.

The form of creel selected to illustrate the invention comprises two frames each having a bottom member 1, a top member 2, and a series of wooden posts 3 connecting the lower and upper frame members 1 and 2. Said creel frames are arranged in V-form as indicated in Fig. 6 their adjacent ends being united by a cross-member 3^a. Means is provided for supporting a vertical row of cross-wound yarn masses *a* behind each of the posts 3. Since the present invention does not relate to the details of the yarn-mass supporting means, it will be sufficient to state that each yarn mass *a* is non-rotatably mounted upon a spindle 4 and that each yarn mass is mounted within a cylindrical casing 5 having a closed rear end and an open front end.

The devices for guiding the yarn in its course from the cheeses to the warper and the means for detecting exhaustion of the yarn are supported upon the posts 3. As shown in Fig. 1 one edge of the post 3 is approximately in the vertical plane of the axes of the row or column of cheeses *a*. This edge

and the adjacent rear corner of the post 3 are covered with sheet metal as shown at 6 in Fig. 2. In passing from the cheese to the detector the yarn runs between the plate 6 and a rod 7, said rod being pivoted at 8 to the upper frame member 2 and extending in front of the vertical row of cheeses to the bottom of the creel. As shown in Fig. 1 the pivot 8 is so located with reference to the post 3 that the rod 7 tends to swing by gravity 10 toward the post 3 into its operative position. The lower end of the rod 7 extends within a stationary frame 9, which prevents displacement of the rod in one direction and 15 permits swinging movement of the rod into the dotted-line position shown in Fig. 1.

Each detector consists of an arm 10 preferably made of a piece of wire bent to form a pivot 11, said pivot being supported in a bearing 12. The arm 10 is in the shape of a 20 loop so as to provide two parallel portions against which the yarn bears. These parallel portions are bent so as to form notches 13 through which the yarn may run. As 25 shown in Figs. 1 and 2 the detector is so mounted that when it is in the running position shown in those views, the notches 13 are just below the projected axis of the cheese. The yarn changes direction at the detector 30 and runs to a comb (not shown) on the warper. The tension of the yarn normally holds the arm 10 in contact with a stop portion 14 (Figs. 2 and 4) against the action of gravity.

Between the detector and the rod 7 the 35 yarn runs through a guide formed of two fingers 15 and 16. These fingers are arranged in parallel closely adjacent vertical planes. The yarn runs between the fingers. As shown in Fig. 2 there is an angular portion 17 which 40 limits downward movement of the yarn. The finger 16 has a projection 18 that limits upward movement of the yarn. The projection 18 extends past the vertical plane of the yarn-guiding edge of the finger 15. The upper 45 side of the projection 18 is inclined so as to allow the yarn to slide down past the projection when the yarn is being inserted into the guide, there being sufficient space between the finger 15 and said projection to permit 50 the yarn to pass below the projection. Owing to the fact that the projection 18 overlaps or extends past the yarn-guiding edge of the finger 15, the yarn cannot disengage itself 55 from the guide fingers 15 and 16 after having passed below the projection 18.

In its swinging movements the detector 60 straddles a finger 19 which is like the finger 16, said fingers being located in parallel vertical planes, as shown in Fig. 5. When the detector swings down due to slackening of the yarn, the latter is carried against the inner edges of said fingers and is thereby drawn into the form of two loops, as shown 65 in Fig. 3.

Parallel with the fingers 16 and 19 is a guide finger 20 which is a continuation of a guide plate 21 that extends down to the next yarn-guiding unit. The lower portion of said guide plate is cut away at 22 so as to extend below the upper part of the next lower guide finger 20, there being a space between the edge 22 and the finger 20 to admit the yarn. For the uppermost finger 20 there is a similar guide plate 23.

The finger 16 is virtually a continuation 70 of a guide plate 24 which extends to the next lower unit, as shown in the middle portion of Fig. 1. (The guide plate 21 is broken away to expose the guide plate 24.) A similar 75 guide plate 25 (Fig. 2) is provided for the uppermost finger 15.

As shown in Fig. 1, the detector extends 80 above the fingers 15, 16, 19 and 20, and when in the position illustrated in said view the upper end of the detector lies behind the guide edges of the plates 21 and 24 or 23 and 25, as the case may be, so that the yarn cannot slip behind the detector in the operation of associating the yarn with the unit. 90

The bearing 12 (Figs. 4 and 5) for the pivot 95 of the detector is carried by a metallic attaching portion 26 which also supports the parts 14, 15, 16, 19, 20, 21 and 24. The attaching portion 26 is in contact with a metal bar 27 in the post 3, said bar being grounded through the creel frame.

When the detector falls into the position 100 shown in Fig. 4 an electric circuit is closed to ground, whereby the warper is stopped. Upon the pivot 11 of each detector is mounted a contact arm 28 which is preferably constructed as described in Patent No. 1,544,055 and is somewhat yielding. The contact arm 105 28 is arranged to swing into contact with an electric conductor in the form of a flat bar 29. All of the bar 29 except the upper end thereof is enclosed within the post 3. It will be seen that the contact arm 28 and the coacting portion 29a (Fig. 4) of the bar 29 constitute an 110 electric switch and that the switch is completely enclosed. The upper ends of the various conductor or control bars 29 are connected in any preferred way (herein indicated diagrammatically at 30 in Fig. 7) to one pole of an electromagnet 31. The other pole of the electromagnet is connected by means of a conductor 32 to a switch 33 which is connected to a ground 34 and to the main line conductors 35 and 36. 37 is a main line 115 switch.

When a detector falls into the position 120 shown in full lines in Fig. 4 a circuit is closed to ground, thereby energizing the magnet 31, whereupon said magnet withdraws a detent 125 that normally renders inoperative the mechanism for throwing out the warper driving clutch and for applying the beam brake.

The means herein shown for driving and 130 braking the warper is substantially similar

to that disclosed in my Patent No. 1,672,470. The main drive shaft 38 (Fig. 6) of the warper carries a drive pulley 39 to which power is communicated through a drive belt 40. The pulley 39 is arranged to be connected to the shaft 38 through a clutch 41 which is operated by an oscillatory cam 42 fixed to a rock shaft 43. The drive shaft 38 also carries the rotatable element of a friction clutch 44 which serves to brake the warper, said brake being operated by means of an oscillatory cam 45 fixed on the rock shaft 43. The movable elements of the switch 33 are mounted on the rock shaft 43. A contractile spring 46 attached to an arm 47 fixed to the shaft 43 tends to turn said shaft in the direction to throw out the drive clutch 41, apply the brake 44 and open the switch 33. The opening of the switch 33 promptly 20 interrupts the flow of current to ground. The spring 46 is normally restrained by means of a detent 48 which is pivoted at 49 and which carries an armature 50 arranged to be attracted by the electromagnet 31. A 25 contractile spring 51 normally holds the detent 48 in contact with a locking segment 52 fixed upon the rock shaft 43. Said segment is provided with a shoulder 53 against which the detent 48 bears when the apparatus 30 is operating normally, and with a shoulder 54 against which said detent bears when the rock shaft 43 is in its intermediate or brake-released position.

Means is provided whereby the detectors 35 are operated to place tension on the yarn upon the stopping of the warper. Said means comprises a crank arm 55 (Fig. 8) fixed to the rock shaft 43, said arm having a pin 56 that lies within an elongated opening 57 in the upper end of a link 58. The lower end of said link is pivoted to a crank arm 59 which is fixed upon a shaft 60. Fast on said shaft is a weighted hand lever 61, said lever normally holding the upper end wall of the 40 elongated opening 57 against the stud 56 (see Fig. 8). The ends of the shaft 60 are connected by suitable means such as gears 62 to rock shafts 63 which are journaled in the creel frame. On the shafts 63 are fixed 45 arms 64 that underlie the control bars 29. An insulator 65 is interposed between each arm 64 and its control bar 29 (see Fig. 2). It will be seen that when the shaft 43 is rocked by the spring 46 to stop the warper, 50 the weighted hand lever 61 is allowed to drop, thus raising the control bars 29. Each of said bars is provided with a series of projections 66, one for each detector unit, said projections having a vertical surface 67 for engagement by the contact arm 28 or by an arm 68 on the pivot 11, depending upon the vertical position of the control bar. In the 55 stopping of the warper and the consequent upward movement of the control bars, the surfaces 67 are carried into engagement with

the contact arms 68, whereby the detectors are swung into the yarn-tensioning position shown in Fig. 3. Inasmuch as the arms 68 engage with a vertically extending surface, as 67, it will be apparent that all of the detectors except the one that was associated with the broken thread will be swung to the same position regardless of slight variations in the vertical positions of the control bars.

Yarn unwinds so freely from the cheeses that it is impracticable to cause the yarn to raise the detectors and slip behind the fingers 16, 19 and 20 by pulling on the yarn. Means is, therefore, provided for holding all of the detectors in contact with the stop portions 14 when the threads from a new set of cheeses are to be drawn forward to the warper. Said means comprises a detent arm 69 (Fig. 10) having a shoulder 70 adapted to support a pin 71 on the weighted hand lever 61. The detent 69 is pivoted at 72 and is provided with a pedal 73. A spring 74 normally holds the detent 69 in contact with the pin 71 (as shown in Figs. 8 and 10). When the hand lever 61 is in the full-line position illustrated in Fig. 10, the control bars 29 are in their lowermost position, wherein the surfaces 67 (Fig. 2) acting on the contact arms 28 hold the detectors in the position indicated in the last mentioned view.

The means for operating the rock shaft 43 to place the warper in operation comprises a hand lever 75 (Fig. 8), said hand lever being pivoted in the warper framework at 76. A contractile spring 77 normally holds the lever 75 in the position shown in Fig. 10, a lug 78 on the lever being in contact with a lug 79 on the warper framework. The hand lever 75 is connected by means of a link 80 to a pivot stud 81 (Figs. 6 and 9) on the segment 52. The stud 81 extends freely through an elongated opening 82 (Fig. 8) in the link 80.

In order to prevent the warper from being driven while the detectors are held up 110 against the stops 14 by the control bars 29 (as in Fig. 2), I provide a locking dog 83 (Fig. 10) pivoted in position to engage a shoulder 84 on the locking segment 52. A contractile spring 85 normally holds the 115 dog 83 out of the path of the shoulder 84, but while the weighted hand lever 61 is in the position shown in full lines in Fig. 10, the dog 83 is held in the path of the shoulder 84 by reason of the fact that the upper end of 120 the link 58 engages a projection 86 on said dog.

The operation is as follows: Assuming that the warper is running and that a thread breaks, the detector for that thread falls into 125 the position shown in full lines in Fig. 4, whereupon the electromagnet 31 (Fig. 7) is energized, the detent 48 is withdrawn from the locking segment 52, and the spring 46 turns the shaft 43 in the direction to throw

out the driving clutch 41 and apply the brake 44, whereupon the warper stops promptly. The switch 33 does not open until after the shoulder 54 on the locking segment 52 is so close to the upper end of the detent 48 that said shoulder will pass the detent before the spring 51 can swing the detent into engagement with the segment. As the shaft 43 turns to stop the warper, the hand lever 61 drops into the position shown in dotted lines in Fig. 10, thus raising all the control bars 29 into the position shown in Fig. 3 and thereby causing all the detectors except the one associated with the broken thread to swing into the tension position illustrated in that view. The operator then draws forward to the warper the broken end attached to the cheese, the detector for that thread being held up by hand, if necessary, to enable the thread to pass into operative relation to the detector and the guide fingers 15 and 16. The operator then finds the thread end on the beam, to facilitate which the operator may set the beam in slow rotation. For this purpose the operator draws the hand lever 75 forward just far enough to allow the dog 48 to slip under the shoulder 54, the turning movement of the shaft 43 being just sufficient to release the brake 44, but not sufficient to throw in the clutch 41. The operator then operates a treadle (not herein shown) to throw in the clutch 41 sufficiently to revolve the beam slowly. The movement of the rock shaft 43 to allow the dog 48 to engage the shoulder 54 is not sufficient to raise the weighted lever 61 from the yarn-tensioning position shown in dotted lines in Fig. 10, nor to close the switch 33. After piecing up the broken thread, the operator may, if desired, again set the beam in slow rotation until it is noted that all the threads are running properly. The operator then pulls the hand lever 75 forward until the detent 48 springs under the shoulder 53, thus turning the rock shaft 43 sufficiently to operate the clutch 41 to drive the beam at running speed, said movement of the rock shaft serving also to raise the weighted hand lever 61 into the position shown in Fig. 8. As the lever 61 rises the control bars 29 descend to the position shown in Fig. 5^a to allow the detectors to assume the position shown in Figs. 1, 2 and 5^a under the tension of the running threads. The detectors remain in the tensioning position shown in Fig. 3 after the warper starts, only long enough to straighten out any kinks in the yarn.

60 The warper may be stopped at will by closing a switch 87 (Fig. 7) to close a circuit through the magnet 31 to ground.

Means of any ordinary or preferred character, such as a warper clock, may be provided to stop the warper when the desired

amount of yarn has been wound upon the beam.

The operation of connecting a new set of thread-ends to a beam is as follows: The operator places the lever 61 in the position shown in full lines in Fig. 10, whereby the detectors are raised into the thread-receiving position shown in Fig. 2. The operator then collects the threads of the column of cheeses which is nearest the warper at, say, the right-hand side of the creel, beginning at the top of the column and drawing the thread-ends down to the bottom, the threads twisting together into a bunch. The operator then draws forward to the warper a convenient number of bunches of threads, each bunch having previously been inserted into the space between the plate 6 and the rod 7. She then lays the threads into the comb on the warper and connects them to the section beam. As the bunches of threads are drawn to the warper, the plates 21 and 24 guide the threads into contact with their respective detectors. The threads also slide down below the projections on the fingers 16 and 19, then entering the guide openings formed by the overlapping fingers 15 and 16. After all the threads have been drawn forward to the beam, the operator lowers the lever 61 to the dotted-line position of Fig. 10, thereby placing the detectors in yarn-tensioning position as shown in Fig. 3. The warper is then started as hereinbefore described.

The plate 6 and the rod 7 define a vertical slot in which the thread traverses up and down as it balloons off the cheese (see Fig. 2). Since the thread traverses only in a vertical line, there is no tendency for the thread to jump out of the guide formed by the fingers 15 and 16; moreover, the cheese may be placed on its spindle 4 either end to, as the balloon may revolve in either direction without causing any difficulty. The feature of confining the thread so that it can traverse only in a vertical line is thus important in that it simplifies the loading of the creel and prevents the thread from jumping out of the guide.

It will be seen that the control bars 29 have three positions, namely, the normal or intermediate position, as shown in Fig. 5^a, the upper or yarn-tensioning position illustrated in Fig. 3, and the lower or threading position represented in Fig. 2.

It will be apparent that the construction herein disclosed is well adapted for the attainment of a notable increase in warping speed. The Barber-Colman high speed warper built in substantial accordance with Patents Nos. 1,544,055 and 1,672,470 is being commercially operated at speeds in the neighborhood of five hundred yards per minute, whereas the apparatus herein shown may be operated at speeds upwards of eight hundred yards per minute. Moreover, the warper may

be accelerated and braked in a shorter time than heretofore, as there are no rotatable supply yarn masses to limit the rate of acceleration or deceleration.

5. This application is a continuation in part of my application Serial No. 283,244, filed June 6, 1928.

10. While the present embodiment of the invention has been described in considerable detail, it will be understood that various modifications of details and rearrangements of mechanism may be made, within the scope of the appended claims, without departing from the spirit of the invention.

15. I claim as my invention:

1. A creel comprising a row of yarn mass supports, a row of detectors, one for each yarn mass support, an electric conductor bar extending along the row of detectors, said 20 bar having a position wherein it coacts with a fallen detector to close a circuit, another position wherein it holds the remaining detectors in yarn-tensioning position, and a third position wherein it holds all the detectors elevated, and means for operating said bar.

2. A creel comprising a row of yarn mass supports, a row of detectors, one for each yarn mass support, an electric conductor bar 30 longitudinally movable along the row of detectors, said bar having means for engagement by said detectors when the latter perform their circuit-closing function, said bar also having means to engage the detectors and move them into yarn-tensioning position, and means automatically actuated when a detector performs its circuit-closing function for moving said bar to move the detectors into yarn-tensioning position.

40. 3. A creel comprising a row of yarn mass supports, a row of detectors, one for each yarn mass support, an electric conductor bar longitudinally movable along the row of detectors, said bar being adapted for engagement by said detectors when the latter perform their detecting function to close an electric circuit, said bar also having a series of projections to engage the detectors and move them into yarn-tensioning position, and means for moving said bar.

45. 4. A creel comprising a row of yarn mass supports, a row of detectors, one for each yarn mass support, a bar longitudinally movable along the row of detectors, said bar having a series of projections thereon to engage the detectors and move them into yarn-tensioning position, and means for moving said bar.

50. 5. A creel comprising a row of yarn mass supports, a row of detectors, one for each yarn mass support, each detector having a contact portion, an electric conductor bar longitudinally movable along the row of detectors, said bar having a series of parts 55 thereon for engagement by said detectors

when the latter perform their detecting functions, said bar also having a series of parts to move the detectors into yarn-tensioning position, means for moving said bar in opposite directions, and means enclosing the contact portions and said parts.

6. A warper creel comprising a supporting member, a series of detectors pivotally supported on said member, each detector having a contact arm, the detector and the contact arm extending in different directions from their axis of pivotal movement, and a control member 70 slidably longitudinally of itself and the supporting member and adapted to engage all of the contact arms to move the detectors into a certain position.

7. A warper creel comprising a supporting member, a series of detectors supported on said member, and a control member movable longitudinally of itself and the supporting member and enclosed within said member and adapted to engage each of the detectors to move them into a certain position.

8. A warper creel comprising supports for non-rotatably holding supply yarn masses 75 for the drawing of yarn off the ends of the yarn masses, detectors on the creel for detecting exhaustion of the yarn being unwound, and means for simultaneously placing the detectors in an intermediate or yarn-tensioning position.

9. The combination of a plurality of detectors for detecting exhaustion of the yarn being unwound, and automatically operable means for simultaneously placing the detectors in an intermediate or yarn-tensioning position, and for simultaneously releasing the detectors from such position.

10. The combination of a row of pivoted detectors each having an electric contact arm, the detector and the contact arm extending in different directions from their axis of pivotal movement, a control bar extending along the row of detectors and having means adapted to be engaged by and to engage said contact arms, an enclosure for said contact arms and means, and means for moving said control bar.

11. A creel comprising a row of yarn-mass supports, a row of detectors, one for each yarn-mass support, means coacting with each detector for placing additional tension on the yarn when the detector is moved into yarn-tensioning relation to said means, and means extending along the row of detectors for moving the detectors into such yarn-tensioning position.

12. The combination of a warper, a drive for the warper, a brake for the warper, a rock shaft on the warper for controlling the drive and the brake, a spring tending to turn the rock shaft in the direction to throw out the drive and apply the brake, a locking segment on said rock shaft, a detent spring-actuated into engagement with said segment, an 125

5 electromagnet for withdrawing the detent from the segment, yarn-controlled means for controlling the electromagnet, and a lever for turning the rock shaft against the tension of the first mentioned spring, said segment having a shoulder for engagement by said

10 13. The combination of a warper, a clutch to drive the warper, a brake for the warper, a rock shaft on the warper for controlling the clutch and the brake, means to turn the rock shaft in the direction to throw out the 15 clutch and apply the brake, a locking segment on said rock shaft, a detent spring-actuated into engagement with said segment, an electromagnet for withdrawing the detent from the segment, yarn-controlled means for controlling the electromagnet, and means for 20 turning the rock shaft in the other direction, said segment having a shoulder for engagement by said detent when the brake is released and the clutch is thrown out, and another shoulder for engagement by said detent when the clutch is in.

14. The combination of a warper, a drive for the warper, a rock shaft on the warper for controlling the drive, means to turn the 25 rock shaft in the direction to throw out the drive, a locking segment on said rock shaft, a detent spring-actuated into engagement with said segment, an electromagnet for withdrawing the detent from the segment, 30 yarn-controlled means for controlling the electromagnet, means to turn the rock shaft in the other direction, said segment having a shoulder for engagement by said detent when the drive is still thrown out, and another shoulder for engagement by said detent when the drive is in.

15. The combination of a warper, a creel, a drive for the warper, a brake for the warper, a rock shaft on the warper for controlling the 40 drive and the brake, a spring tending to turn the rock shaft in the direction to throw out the drive and apply the brake, detectors arranged to control the spring, means coacting with each detector for placing additional 45 tension upon the yarn when the detector is moved into yarn-tensioning relation to said means, and automatically-actuated means for moving the detectors into such yarn-tensioning position upon operation of the spring.

50 16. The combination of a warper, a creel, a brake for the warper, detectors on the creel arranged to control the brake, means coacting with each detector for placing additional tension upon the yarn when the detector is 55 moved into yarn-tensioning relation to said means, and automatically-actuated means for moving the detectors into such yarn-tensioning position upon application of the brake.

17. The combination of a warper, a creel, 60 a drive for the warper, a brake for the warper,

means for controlling the drive and the brake, detectors on the creel, and automatically-actuated means for simultaneously moving the detectors upon operation of the drive and brake controlling means.

70 18. The combination of a warper, a creel, a rock shaft controlling the warper, a locking member on said shaft, a dog to engage the locking member to prevent movement of the shaft in the direction to start the warper, a spring tending to withdraw the dog, detectors on the creel, mechanism for holding the detectors in inoperative position, and a connection between said mechanism and said dog to render the latter operative when the 75 detectors are thus held.

19. The combination of a warper, locking means to prevent starting of the warper, detectors for the yarn being wound, mechanism for holding the detectors in inoperative position, and a connection between said mechanism and said locking means to render the latter operative when the detectors are thus held.

80 20. The combination of a warper, a creel, detectors on the creel, means for holding the detectors elevated, and means to prevent the warper from being started when the detectors are thus held.

85 21. The combination of a warper, a creel for non-rotatably supporting supply yarn masses, means for stopping the warper, and yarn-tensioning means which acts upon the individual yarns at points close to the supply yarn masses and is automatically rendered effective only upon operation of said stopping means.

90 22. The combination of a warper, a creel for non-rotatably supporting supply yarn masses, individual tensioning means for each of the threads being wound, said means acting upon the threads at points close to the supply yarn masses, means to start the warper, and means actuated in the starting of the warper for rendering the tensioning devices inoperative.

95 110 23. A creel comprising a row of yarn mass supports, a row of detectors, one adjacent to each yarn mass support, a control bar of electrical conducting material extending along said rows, each detector having a circuit-closing arm and an arm for moving the detector into yarn-tensioning position, said bar having a series of projections, each projection having a flat longitudinally extending end surface to engage said arms, and means for longitudinally moving said bar to control the detectors.

115 In testimony whereof, I have hereunto affixed my signature.

BURT A. PETERSON.
